UNITED STATES PATENT OFFICE.

FRANK J. BLUM, OF DANSVILLE, NEW YORK, ASSIGNOR TO BLUM SHOE MANUFACTURING CO., OF DANSVILLE, NEW YORK.

COLD-RESISTING SHOE.

1,201,928.

Specification of Letters Patent. Patented Oct. 17, 1916.

Application filed June 22, 1916. Serial No. 105,254.

To all whom it may concern:

Be it known that I, FRANK J. BLUM, a citizen of the United States, residing at Dansville, in the county of Livingston and State of New York, have invented certain new and useful Improvements in Cold-Resisting Shoes; and I do declare the following to be a full, clear, and exact description of the invention, such as will enable others skilled in the art to which it appertains to make and use the same.

My invention relates to improvements in boots and shoes and more particularly to the latter, the object of the invention being to provide a comparatively inexpensive yet highly desirable cold resisting shoe which may be easily made by machine operations, said shoe having a lining of sheared and carded wool extending not only over the sides of the upper but over the sole of the shoe to form a warm and comfortable inner sole.

With this general object in view, the invention resides in certain novel features of construction and in unique combinations of parts to be hereinafter fully described and claimed, the descriptive matter being supplemented by the accompanying drawings which constitute a part of this application and in which:

Figure 1 is a perspective view of the improved shoe; Fig. 2 is a horizontal sectional view thereof; Fig. 3 is a vertical longitudinal section through the shoe taken on the plane indicated by the line 3—3 of Fig. 2; Fig. 4 is a vertical transverse section taken on the plane of the line 4—4 of Fig. 3; Fig. 5 is a perspective view of the shoe immediately before applying the sole; and Fig. 6 is a vertical transverse section through the toe of a modified form of the invention.

In specifically describing the construction shown in the drawings above briefly described, similar characters will be placed on corresponding parts throughout the several views, and reference will be herein made to the numerous elements by their respective indices. To this end, the numerals 1 designate the two halves or sides of the upper, each of said halves consisting of an outer backing sheet 2 of felt or other suitable material, and a lining 3 of sheared and carded wool in its natural state, said lining being

secured to the backing sheet 2 by machine quilting as shown at 4.

The two halves 1 are suitably shaped and are stitched together at their rear edges, as indicated at 5, while the lower ends of their front edges are similarly attached by stitches 6, the upper portions of said front edges, however, being bound at 7 and having eyelets or the like 8. The binding 7 preferably extends along the upper edges of the two halves 1 of the upper, although this exact construction need not be followed too closely.

The lower edges of the two halves 1 of the upper are curved inwardly and stitched together at 9 from their front ends to a point in advance of their rear ends to form a bottom 10 for the shoe having a slit 11 at its rear end through which slit the heel counter 12 is inserted when constructing the shoe, said counter being disposed in contact with the inner surface of the lining 3 and preferably having its lower edge turned inwardly at 13 above the inwardly directed lower edges of the halves 1 (see more particularly Fig. 4).

A supplemental lining 14 is disposed over the counter 12, said supplemental lining being preferably formed of a single strip of felt or the like whose lower edges are turned inwardly above the portions 13 of the counter, while the upper and front edges of said strip are stitched at 15, through the backing sheet 2 and the lining 3. Said lower edges of the lining 14 are united by stitching 9^a which forms a continuation of the row of stitching 9.

An arch support 16 which will preferably though not necessarily be constructed of heavy cardboard, extends beneath the instep of the bottom 10 and is cemented thereto, the lower surface of said member 16 being preferably cemented to the outer sole 17 which is stitched or otherwise secured to the bottom 10, said sole having a heel 18. As is usual, a small gap 19 is left in the bottom 10 adjacent the front end thereof to permit proper lasting of the shoe but the fibers of the lining 3 will sufficiently fill this gap to prevent the same from being uncomfortable to the wearer.

In Fig. 6, a vertical section through the toe of a modified form of shoe is shown, this type being identical with that previously de-

scribed with the exception that it is provided with a covering 20 of leather or other suitable material. This covering may be in some cases constructed of felt, but in either case, 5 the backing 2 may be of a cheap yet durable grade of material.

I have found from actual experience that the sheared and carded wool lining 3 in its natural state secured in place by machine 10 quilting forms a most effective cold resisting medium and obviously by turning the lower edges thereof inwardly and connecting them, an effective inner sole is provided. Furthermore, the interior of the shoe will 15 be extremely comfortable to the user, since although a number of seams prevail, the stitches thereof are so embedded in the soft natural wool as to prevent chafing of the wearer's feet.

20 The fact that the seam 9^a rests on the soft wool lining 3 at the edges of the slit 11 is a rather salient feature since in use said seam may sink into said lining and will thus be in no manner uncomfortable to the wearer.

25 From the foregoing taken in connection with the accompanying drawings, the construction and advantages of the improved shoe will be readily understood without requiring a more extended explanation. In 30 conclusion, however, I wish to state that although I have shown and described certain specific details for accomplishing probably the best results, numerous changes may be made within the scope of the invention as 35 claimed without sacrificing the main advantages thereof.

I claim:

1. A cold resisting shoe comprising an upper having the lower edge portions turned

inwardly to form a bottom, and a lining of 40 soft material extending over the upper and bottom and quilted to both.

2. A cold resisting shoe comprising an upper having the lower edge portions turned inwardly to form a bottom, and a lining of 45 soft material extending over the upper and bottom and quilted to both, the inturned edges of said upper being stitched together and the stitches being so embedded in the soft lining as to prevent said stitches from 50 chafing the wearer's foot.

3. A cold resisting shoe comprising an upper having the lower edge portions turned inwardly to form a bottom, a lining of soft material extending over the upper and bottom and quilted to both, the inturned edges being stitched together from their front ends to points in advance of their rear ends and the stitching being so embedded in the lining as to prevent chafing of the wearer's 60 foot, a slit being left between the rear ends of said edges to permit the insertion of a heel counter, a heel counter in the heel of the shoe in contact with the inner side of the lining, and a supplemental lining secured over said counter and having its lower edges turned inwardly and stitched together, the stitching being disposed over the aforesaid slit, whereby it may sink into the soft lining at the edges thereof to prevent 65 discomfort to the user.

In testimony whereof I have hereunto set my hand in the presence of two subscribing witnesses.

FRANK J. BLUM.
